UNITED STATES PATENT OFFICE

GUSTAV JOHNSON, OF WEST ROXBURY, MASSACHUSETTS, ASSIGNOR TO UNITED-CARR
FASTENER CORPORATION, OF CAMBRIDGE, MASSACHUSETTS, A CORPORATION OF MASSACHUSETTS

SLIDE FASTENER AND INSTALLATIONS THEREOF

Application filed January 5, 1931. Serial No. 506,543.

My invention aims to provide improvements in slide fasteners and slide fastener installations for gloves, overshoes and other like means wherein a strap is used in combination with a separable snap fastening means.

In the drawing which illustrate preferred embodiments of my invention:

Figure 1 is a plan view of a slide fastener installed as used on a strap;

Fig. 2 is an enlarged section taken on the line 2—2 of Figure 1;

Fig. 3 is a rear view of the slide member and strap shown in Figs. 1 and 2, the parts being shown in position for easy adjustment of the slide relative to the strap;

Fig. 4 is a section taken on the line 4—4 of Fig. 3;

Fig. 5 is a view similar to Fig. 3, but showing the parts in locked position relative to the strap;

Fig. 6 is a section taken on the line 6—6 of Fig. 5;

Fig. 7 is an edge view of the slide member shown in Figs. 1 to 6;

Fig. 8 is an edge view of a modified form of slide fastener; and

Fig. 9 is a rear view of the slide fastener shown in Fig. 8.

Referring to the drawing and particularly to that form of device shown in Figs. 1 through 7, I have provided a slide fastener installation which comprises a separable snap fastening means combined with a strap and adapted for adjustment. The separable fastening means includes a stud and a socket both of which may be adjustable or one only of which may be adjustable on the part carrying it. In Figs. 1 and 2 I have shown a stud 1 fixed to one end of a strap or belt 2 and a sliding socket device adjustably located at the other end of the strap 2.

The particular sliding socket device shown in Figs. 1 through 7 comprises a top plate

3 which is preferably imperforate and of ornamental design, an underlying fastener-carrying plate 4 and a socket means 5 carried by the plate 4. The stud 1 and socket means 5 may be of any suitable construction and may be reversed as to location without affecting the idea of my invention.

It is a feature of my invention to secure the parts 3 and 4 together in such a manner that there can be relative transverse movement. Therefore, I have made the top plate 3 somewhat dish-shaped and bent portions 6 and 7 extend over the fastener-carrying part 4 to hold the two parts in assembly, as shown in Fig. 3. The end portions 8 and 9 of the part 4 are bent at right angles (Fig. 2) to space that part from the part 3 thereby providing for a space between the parts 3 and 4 for the passage of the strap 2.

In the particular design of the slide fastener shown in Figs. 1 through 7 the lower end and the portions 7 of the top plate 3 provide a pocket in which the rounded end 10 of the plate 4 is pivoted so that the top plate 3 may move with the strap 2 relative to the fastener-carrying part 4 when it is engaged with the stud 1 by means of the socket means 5. Thus when the strap carrying the slide member is placed under lateral stress relative to the stud 1 the plate part 3 will pivot relative to the plate part 4, thereby clamping the strap 2 between an edge of the part 4 and an edge of the part 3, as clearly shown in Figs. 5 and 6. As shown in Fig. 7, prongs 11 are preferably provided at the edges of the top plate 3 to engage the strap thereby to help move the top plate when the installation is under lateral stress and to help grip the strap and prevent its slipping through the slide fastener.

To adjust the slide member relative to the strap 2 or to secure it thereto it is merely necessary to move the parts 3 and 4 relative to each other so that they assume a central

relation, as shown in Figs. 3 and 4. Then the spaces between the edges of the part 3 and the edges of the part 4 are sufficient to permit relatively easy passage of the strap 2.

5 In Figs. 8 and 9 I have shown a slide fastener member which operates on the same general principles as the one above described. In this particular fastener, however, the parts 3 and 4 are rectangular in outline and the 10 movement of one part relative to the other is in a straight line instead of one part being pivoted relative to the other. Furthermore, I have provided two prongs 11 at each edge of the part 1 instead of one and I have also 15 provided ears 12 on the edges of the part 4 for engagement with the strap thereby providing a firmer grip on the strap when lateral stress is exerted upon the strap.

20 My slide fastener provides an improved installation. It is easier to apply because of the lack of slots, as in most other slides, and it holds better under lateral stress. It is easy to adjust, simple in construction, durable and relatively inexpensive to manufacture. 25 Furthermore, it is decidedly adapted for ornamentation since the top plate is imperforate and may be made in substantially any desired shape.

30 While I have illustrated and described two embodiments of my invention I do not wish to be limited thereby, because the scope of my invention is best defined by the following claims.

35 I claim:

1. A slide fastener for straps and the like comprising, in combination, a top plate part, a fastener-carrying plate part assembled with and located entirely beneath said top plate part, said plate parts being superposed in spaced relation to provide a strap-receiving space between opposite faces for the passage of a strap, snap fastener means carried by said fastener-carrying plate part for engagement with a cooperating snap fastener means and means cooperating between the two plate parts to hold them in assembled relation while permitting movement of one in a flat plane relative to the other to grip the strap between said plate parts.

40 2. A slide fastener installation comprising, in combination, a slide device comprising two plate members, one being superposed upon the other in a manner to provide a strap-receiving space between them, a strap passing through the space between said plate members, means supporting one of said plate members loosely relative to the other to permit movement thereof and means provided by 45 said plate members whereby when said loosely supported plate is moved in a flat plane generally longitudinal relative to the strap the strap will be clamped between said plate members, and one element of a snap fastener carried by one of said plate members.

3. A slide fastener installation comprising, in combination, a slide device comprising two plate members one being superposed upon the other, a strap passing between said plate members, means supporting one of said plate members in transversely pivoted relation to the other to permit movement thereof only in a plane parallel to the plane of the other plate member and means provided by said plate members whereby when said pivoted plate member is moved the strap will be clamped between said plate members, and one element of a snap fastener carried by one of said plate members.

4. A slide fastener installation comprising, in combination, a slide device comprising two plate members, one being superposed upon the other, a strap passing between said plate members, means supporting one of said plate members loosely relative to the other to permit movement thereof only in a flat plane relative thereto and a strap-engaging projection provided on the edge of one of said plate members thereby to aid in the operation of one part relative to the other and also to aid in the gripping action and one element of a snap fastener carried by one of said plate members.

5. A slide fastener for straps and the like comprising, in combination, two plate members secured together and adapted to be attached to a strap for sliding movement relative thereto, one of said plate members being spaced from the general plane of the other to provide a space between the plate members through which the strap may pass, and said plate members being movable relative to the other for clamping the said slide fastener to the strap, snap fastener means carried by one of said plate members only for cooperative engagement with another snap fastener means and prongs provided on the other plate member for gripping the strap which passes between said plate members.

6. A slide fastener for straps and the like comprising, in combination, two plate members secured together and adapted to be attached to a strap for sliding movement relative thereto, one of said plate members being spaced from the general plane of the other to provide a space between the plate members through which the strap may pass, and said plate members being movable relative to the other for clamping the said slide fastener to the strap, snap fastener means carried by one of said plate members only for cooperative engagement with another snap fastener means and prongs provided on both of said plate parts for gripping the strap to which the fastener is to be attached.

7. A slide fastener for straps and the like comprising, in combination, two plate members secured together and adapted to be at-

tached to a strap for sliding movement relative thereto, one of said plate members being slidably movable relative to the other for clamping the said slide fastener to the strap,
15 snap fastener means carried by one of said plate members for cooperative engagement with another snap fastener means and spacing means provided between said plate parts to provide a space through which a strap
20 may slide relatively freely when the parts are central to each other.

In testimony whereof, I have signed my name to this specification.

GUSTAV JOHNSON.
